COMBINATION HAIR WAVE GAUGE, COMB,
AND RAZOR

Louis Quinio, Tarentum, Pa.

Application December 2, 1940, Serial No. 368,145

2 Claims. (Cl. 132—45)

This invention relates to new and useful improvements in a combination hair wave gauge, comb and razor, and it is among the objects thereof to provide a comb and razor unit which is especially adapted for use by hairdressers and barbers in the cutting and trimming of hair to adapt it for styling and waving.

My present invention is an improvement of a wave gauge and comb disclosed in my Patent No. 2,166,558 granted July 18, 1939, in that it can be converted from a gauge and comb to a comb and razor unit, and in that it can be folded when not in use.

The invention will become more apparent from a consideration of the accompanying drawings 15 constituting a part hereof in which like reference characters designate like parts and in which:

Fig. 1 is a top plan view of a gauge comb and razor embodying the principles of this invention;

Fig. 2 is a side elevational view thereof;
Fig. 3 a cross-section taken on the line 3—3,
Fig. 1;

Fig. 4 a cross-section taken on the line 4—4, 25 Fig. 1;

Fig. 5 a top plan view of a modified form of gauge comb and razor;

Fig. 6 a side elevational view thereof;
Fig. 7 a cross-section taken along the line 7—7, 30 Fig. 5; and

Fig. 8 a cross-section taken on the line 8—8,
Fig. 5.

With reference to Figs. 1 to 4 inclusive of the drawings, the structure therein illustrated comprises a combination gauge and comb designated by the reference numeral 1 having rows of teeth 2 and 3 and a handle portion 4, the teeth 3 forming a straight row and the teeth 2 being formed on a curve, which curve is generally of the shape of the human head and may be used as a gauge for hair waving, the handle portion 4 being similarly curved.

The handle 4 is adapted to be folded on the joint 5 by means of the hinge construction shown in Figs. 2 and 4, which consists of the hinge lugs 6, 6a, on the handle portion 4, and hinge lugs 7, 7a, on the comb portion 1. A coil spring 8 is disposed between the hinge lugs 6a and 7, as shown in Fig. 4, and the hinge lugs are provided with offset shoulder portions 9 that interact to lock the handle in its extended position.

A hinge pin 10 extends through the hinge lugs 6, 6a and 7, 7a, and is peened over at its ends to prevent displacement. The handle portion 4 can

be folded, as shown by the arrows and dotted lines in Fig. 2 by merely displacing it along a straight line axially of the hinge pin, as shown by the arrow in Fig. 1, which disengages the hinge lugs 6, 6a, from the members 7, 7a, and permits folding of the handle portion 4.

The comb portion 1 is provided with slide brackets 11, 11a, Fig. 3, for receiving razor blades 12, 12a, which are mounted by moving or sliding them in the brackets 11, 11a, as shown by the dotted lines and arrows in Fig. 1.

In the modification shown in Figs. 5 to 8 inclusive, a comb portion 13 is hinged to a handle portion 14 by a pivot pin 15, the coacting ends of the comb and handle 13 and 14 being rounded as shown in Fig. 5. The handle is locked in its open position by a pin 16 which is mounted on a spring plate 17 attached to the comb portion by riveting at 18, the spring plate 17 carrying a button 19 which may be depressed by the thumb to release pin 16 from the opening 16a in the handle portion 14.

The handle portion is further provided with a perforation 20 for receiving the lock lug 16 when in the folded position, the folded position being shown by dotted lines in Fig. 5 of the drawings.

The comb portion 13 is provided with teeth 21 and 22 and with slide brackets 23 and 24 for receiving the razor blades 25 and 26. This construction is different from that shown in Fig. 1 by having blades on opposite sides of the comb instead of both sets of blades on one side of the comb. The comb may be used with or without blades or with one blade instead of the two as the operator may desire.

The combination gauge comb and razor is useful as a wave set gauge and cutting comb to strip the hair, particularly the surface hair to remove the outer layers of the hair to permit it to assume a natural contour as guided by the gauge during the process of trimming as described in the aforementioned patent previously granted me.

By the use of the cutting blades directly on the comb, the hair cutting and wave setting operation is greatly facilitated as the operator has all of the tools required in one hand, thereby having the freedom of bunching and holding the hair at the point of operation.

Although several embodiments of the invention have been herein illustrated and described, it will be evident to those skilled in the art that various modifications may be made in the details of construction without departing from the principles herein set forth.

I claim:

1. A combination hair wave gauge comb and cutter comprising a thin flat strip with teeth extending transversely of a straight longitudinal axis of said strip on opposite edges thereof and having portions of its longitudinal edges curved, a razor mount integrally attached on a flat face thereof, said razor mount being disposed adjacent the teeth of the strip, and a blade secured in said mount with its cutting edge disposed 10

transversely of the teeth to cut the hair drawn through the teeth of the comb.

2. A hair wave gauge comb and cutter as set forth in the next preceding claim characterized by a hinged joint at substantially the longitudinal center thereof for folding the handle and comb portion and means for locking the joint in the open position.

LOUIS QUINIO.
